ELECTRICITY CONDUCTOR UNIT AND
METHOD OF USING SAME

Joseph F. O'Brien, Jersey City, N. J., assignor to
John B. Pierce Foundation, New York, N. Y.,
a corporation of New York

Application March 13, 1941, Serial No. 383,089

16 Claims. (Cl. 174—88)

This invention relates to improved conductor units for electric wiring systems, and to a method of using the same.

In particular, the invention relates to wiring systems in which individual conductor-carrying units of predetermined and preferably standard lengths are interconnected, in seriatim, to form a continuous electrical circuit.

It is an object of the present invention to provide means whereby one of said seriatim-connected units may be shortened to meet a specific condition of installation, without mutilating or otherwise altering the configuration of the end portions of such shortened unit, or disturbing the continuity of the electrical conductors within said unit.

A further object of the invention is an electrical conductor-carrying unit of which the end portions are arranged for male and female connection with contiguous conductor-carrying units, said electrical conductor-carrying unit having means whereby it may be shortened without alteration of the male or female end portions thereof.

A further object of the invention is to provide an electrical conductor unit having a base portion without which, or associated with which, are electricity conductors in mutually insulated spaced relationship, and a cap portion, removable from said base portion, having an outer configuration preferably matching that of the electricity conductor units with which the instant conductor unit is adapted to be interconnected. One end of the base portion may be configured to provide the male connection portion of the unit, and the opposite end of the cap portion may have a configuration suitable for the female connection portion of the unit. In preferred forms of the invention means are provided to secure the cap and base portions firmly together, and also to establish an exact relationship of the cap and base portions upon the interassembly thereof.

Reference is herein made to my co-pending application Serial No. 279,086, filed June 14, 1939, entitled Conductor unit for electrical wiring system.

Other features and advantages will herein-after appear.

In the accompanying drawings:—

Fig. 1 is a representation of a series of electrical conductor-carrying units, arranged in seriatim to provide a continuous electrical circuit;

Fig. 2 is a plan view, partly in section, illus-

trating a method of serially interconnecting contiguous conductor-carrying units;

Fig. 3 is a vertical section of the assembled units of Fig. 2;

Fig. 4 is a vertical section taken on the lines 4—4 of Fig. 3, enlarged to show detail;

Fig. 5 is a perspective of a conductor-carrying unit embodying the subject matter of the present invention, said unit being inverted to show the separability of the component parts of the said unit;

Fig. 6 illustrates the manner in which the unit of Fig. 5 may be cut, after separation of the component parts thereof, to shorten the unit;

Fig. 7 illustrates the relative position of the component parts of said unit, preparatory to reassembly;

Fig. 8 is a perspective of the cap and base portions of a second form of unit, separated to show features thereof;

Fig. 9 is a section taken through an assembled conductor unit of the Fig. 8 type, particularly showing the keyed securement of the cap and base portions by the tongue and groove configuration of the side walls thereof;

Fig. 10 is a perspective view, partly broken away to show structural details, of a switch unit embodying the instant invention;

Fig. 11 is a section similar to the section of Figure 9, showing a second form of keyed securement of the cap and base portion; and

Fig. 12 is a similar section showing another method of securing the cap and base portions against separation.

Referring to the drawings, Fig. 1 illustrates a fraction of a continuous wiring system comprised of serially interconnected units 10 and 11.

Desirably, the units 10 have an overall length of sixteen inches or any convenient multiple thereof, to allow for securement to wall studs spaced sixteen inches on centers pursuant to standard building practice.

Obviously, the desired length of the wiring system may not permit the interconnection of an equal number of the said sixteen inch units 10, and it is desirable, therefore, to provide units 11, the length of which is any suitable fraction, preferably one-third, of the length of a sixteen inch unit 10, to facilitate the installation of the wiring system with a minimum of cutting.

Further to increase the adaptability of said units 11, the present invention comprehends a novel construction whereby said units may be cut to desired length at the site of installation.

in a manner which does not disturb or disarrange the male and female end portions thereof, or interrupt the continuity of the conductors therein.

The units 10 and 11 incorporate preferably tubular conductors 12, 12 uniformly positioned, during manufacture, in predetermined spaced relationship.

The units 11, in the various forms disclosed herein, comprise a cap member, generally designated 13, and a base member, 14, arranged for positioning within said cap portion in such manner as to make the said base portion removable therefrom. The cap and base members of the respective embodiments have distinguishing characteristics specifically referred to herein-after.

To facilitate the manufacture of the base portion, it is desirable to form it in two sections, 15, 16, each section being preferably channel shaped, and so related that the web portions of each channel are in surface contact. The conductors 12, 12 may advantageously be positioned within the base 14 by providing the webs of the channel members 15, 16, with hemi-cylindrical grooves which combine to form continuous, longitudinally extending, tubular passages. If such resulting tubular passages are equal to the outside diameter of the tubular conductors 12, the said conductors are thereby firmly secured within the base 14 in a predetermined, fixed, spaced relationship. The respective portions 15 and 16 of the base 14 may be of any suitable electrical insulation material, such as rubber, or suitable molded plastic, whereupon individual insulation of the conductors 12 is unnecessary.

In the form of the invention shown in Fig. 4, the respective elements 15 and 16 of the base 14 may be secured by a suitable adhesive, or assuming rubber or suitable plastic material to be used for said members, the members 15 and 16 may be partially cured, the tubular conductors positioned therein and the curing completed to adhesively bond the respective elements together to form the completed base 14. To facilitate the positioning of the respective elements of the base portion, it may be desirable to provide the member 15 with a pin formation 17 adapted to be inserted into a suitable socket in the web surface of the lower member 16, see Fig. 4.

In the embodiments of the invention disclosed in Figures 9 through 12, the component portions 15 and 16 of the base member 14 are shown as secured by any suitable plurality of rivets 18.

Referring again to Fig. 4, it is seen that side walls of the base member 14 of this embodiment converge upwardly and that the inner wall surfaces of the cap 13 have a complementary slope to engage the walls of base portion 14 throughout. Such slope of the walls of the cap 13 and the base 14 facilitates the separation and the re-assembly of such cap and base portions. By having the walls in such sloping association, it is possible to insure a tight face to face engagement thereof, without possibility of binding or adhesion; and the rotation of the base portion outwardly from the cap, as suggested in Figure 5, immediately breaks the association between the elements and the separation results without undue straining.

Referring to the embodiments of Figures 3 and 9, it is seen that the side walls of the members 13 and 14 are substantially vertical and that they are keyed against an outward sepa-

ration by a tongue and groove organization. In the embodiment shown, the base portion is provided with longitudinal grooves 20, said grooves being readily formed by suitably chamfering the side edges of the channel members 15 and 16 so that when said members are secured as shown, a completed groove is formed. The side walls of the cap member 13 are provided with suitable tongues 21, 21, positioned for operative association with the grooves 20 of the base member. It is apparent that the tongue and groove organization permits the base 14 to be slid outwardly of the cap 13, but that a vertical separation of the cap and base member, permitted by the configuration of the Fig. 4 embodiment and illustrated in Fig. 5, is effectively restrained.

In Fig. 11, the keyed association of the cap and base portions is accomplished by an interlocking wedge configuration of such portions, it being observed that the side walls of the base 14 and of the cap 13 are upwardly divergent, to interlock the respective parts against withdrawal except by sliding the base 14 longitudinally outwardly.

In the Figure 12 embodiment, the cap member 13 is provided with inturned flanges 13a, 13a which form trackways to slidably receive the base member 14 and permit separation of the base member 14 and the cap member 13 only by sliding the said base member outwardly.

In the embodiments of Fig. 9 and Fig. 12, it is desirable to have the inner side walls of the cap member 13 formed with a slight slope, rendering it necessary to spread the walls slightly apart during the insertion of the base 14. Such arrangement takes advantage of the resilience inherent in the configuration of the cap 13, causing the side walls of such cap to embrace the sides of the base 14 tightly, and making necessary a positive muscular effort to separate the respective cap and base portions.

In the embodiment of Figure 10, the cap element of the unit, designated 113, embodies a switch mechanism, as is fully shown and described in my co-pending application Serial No. 283,160, filed July 7, 1939, now Patent No. 2,239,654, dated Apr. 22, 1941, and entitled Electrical switch unit. An end 113a of such cap portion remote from the switch is arranged to receive one or the other of the specific forms of base member 14, previously described; in the illustration, such base portion has the grooved organization shown in Figure 8, and the cap portion will, therefore, be provided with tongues 21 (not shown) to cooperate with such grooves.

As clearly appears in Fig. 2, a feature of the seriatim connected electrical units forming the subject matter of this invention is the male and female interconnection of contiguous units, and to effect such interconnection, each unit is provided with a standardized female socket portion 30 at one end, and a standardized male extension portion 33 at the other end. Standardization of the socket and extension portions provides complete interchangeability of units in interconnecting units to form a wiring system.

In the embodiment illustrated in Figure 4, the female socket portion 30 results from a suitable configuration of the inner walls of the cap member 13 at the end thereof, in combination with an end wall 31 of the base member 14, the latter abutting against a squared shoulder 32, as shown clearly in Fig. 2.

The shoulder 32 of the cap member definitely

limits the insertion of the base member 14 within such cap, and by standardizing the configuration of the male extension 33 of such base 14, it will be clearly apparent that when the base member 14 is inserted into the cap 13 to the point of abutment of its end wall 31 against the wall 32, the male extension portion 33 of the base 14 will extend beyond the end of the cap member 13 in definite and predetermined degree.

In the embodiment of the invention characterized by Figure 8, the cap member 13 may or may not have a shoulder formation 32 at its female end. It will be seen from Figure 8 that the grooves 28 in the side walls of the base member 14 terminate at a definite location with respect to the male end 33 of such base; the termination of the grooves provides abutments against which the ends of the tongues 21 will strike when the base 14 is slid into the cap 13, thereby limiting the position of the respective cap and base members.

A further index to establish the proper position of the base 14 with respect to the cap 13, shown in Figure 8, may comprise a mark inscribed on the male member 33; preferably such index is in the form of a groove 34 or like device which is proof against obliteration.

The embodiments of Figures 11 and 12, not having the tongue and groove organization of Figure 8, may employ either the shoulder 32 shown in Figures 6 and 7 or the index 34 shown in Figure 8, or a combination of both, to establish the proper extent of insertion of the cap and body members. The Figure 10 embodiment is provided with the tongue and groove assembly shown in Figure 8, and, therefore, is self-positioning by reason of the abutment of the tongues against the termini of the grooves, as previously described.

As clearly appears in Figure 2, the uniformity of positioning of the conductors 12, 12 within the units insures that the conductors of contiguous units will be in proper registry when the units are arranged in seriatim. Accordingly, suitable means such as the electrically conductive, tapered, pins 36, 36 may be employed to electrically interconnect the conductors 12, 12 of the contiguous units. Such pins 36, 36 likewise serve in part to mechanically interconnect the units, but to afford a positive mechanical interconnection, it is desirable to provide a passage 31 through the male end 33 of a unit and a passage 38 through the top wall of the cap 13 at the female socket end thereof. As appears in Figure 3, the respective passages 31, 38 are so arranged that the passage 38 of a cap unit registers with a passage 31 of the base portion of the preceding unit, and accommodates a wood screw 39 or the like which may incidentally be used to secure the assembled units to the studding or wall partition of the building in which the installation is made.

A feature of the instant invention is the ease with which a unit 11 may be shortened to meet the conditions of an installation, without mutilating the end construction of the unit or interrupting the continuity of the conductors therein. As is shown in Figure 6, such shortening may be accomplished by separating the cap and base members 13, 14 and so arranging the members that the unconfigured ends, that is, the end of the base member remote from the male extension 33 and the end of the cap member remote from the female socket 38, are in alignment, as shown. Then, by cutting the unwanted surplus away from both cap and base portions

simultaneously, as suggested by the broken line in Figure 6 and re-assembling the cap and base portions in the manner suggested in Figure 7, the base member 14 will interfit with the cap member 13 in a manner which provides precisely the same depth of female socket, and precisely the same extent of projection of the male extension 33, as was present in the original unit. The operation of cutting the unit may advantageously be carried out in a mitre-box or the like to provide square lines of severance. It is, of course, possible to cut the desired amount from the cap and base portions individually, providing care is taken in measuring the amount to be cut therefrom, and to establish a square line of severance.

Whereas I have described my invention by reference to specific forms thereof, it will be understood that many changes and modifications may be made without departing from the spirit of the invention.

I claim:

1. A conductor unit for an electric wiring system, comprising a base portion extending substantially the full length of the unit, electrical conductors insulatedly mounted therein, each of said electrical conductors having a length coextensive with the unit, a removable cap portion for bodily telescoping relative with said base portion, said cap portion and said base portion cooperating when in telescoped relation to provide a male end and a female end for seriatim male and female connection and registry of said electrical conductors respectively with the electrical conductors of like polarity of like contiguous conductor units, and means for establishing a desired relative position of cap portion with respect to said base portion.

2. A conductor unit for an electric wiring system, comprising a base extending substantially the full length of the unit, electrical conductors insulatedly mounted therein, each of said conductors having a length coextensive with the unit, a removable cap for bodily telescoping relative with said base, said cap and said base cooperating when in telescoped relation to provide a male end and a female end for seriatim male and female connection and registry of said electrical conductors respectively with the electrical conductors of like polarity of like contiguous conductor units, and means associated with said cap to gage the relative positions of assembly of said base and cap to afford uniformity of the male and female elements of said assembled conductor unit.

3. A conductor unit for an electric wiring system comprising a cap having a top and side walls depending therefrom, a base having a length substantially the full length of the conductor unit and arranged to be removably housed within said cap, electrical conductor means insulatedly mounted within said base portion and coextensive therewith, the top and side walls of said cap and the end wall of said base cooperating to define a socket, and means for gaging the position of said base with respect to said cap to insure uniformity of said socket.

4. A conductor unit for an electric wiring system, comprising the combination with a base having upstanding side walls having convergent outer surfaces and a web, electrical conductors electrically insulatedly disposed within said web and each having a length coextensive with the length of the conductor unit, said base portion having substantially the length of the conductor

unit, of a cap arranged for separable association with said base and having side walls with divergent inner faces for mating contact with the side wall surfaces of the base, said cap and said base cooperating, upon assembly, to provide a male end and a female end for male and female association with contiguous units in seriatim assembly, said cap portion having means effective to gage the position of its associated base portion with respect thereto, to insure uniformity of the said male and female ends.

5. A conductor unit for an electric wiring system comprising a cap having a top and side walls depending therefrom, a base having a length substantially the full length of the conductor unit and arranged to be removably housed within said cap, electrical conductor means insulatedly mounted within said cap, electrical conductor means insulatedly mounted within said base portion, the top and side walls of said cap and the end wall of said base cooperating to define a socket, and shoulder means provided in said cap to establish the position of the end wall of said base with respect to said cap.

6. A conductor unit for a wiring system, comprising a cap member, a base arranged to be removably secured to said cap member, said base having an end portion arranged for projection beyond an end of said cap member when said cap member and base are in operative association, electricity conductor means arranged within said unit in mutually insulated spaced relationship and extending longitudinally of said unit, and means on said cap member for gaging the relative position of said cap member and base to afford a uniform extent of projection of said base end portion with respect to said cap member.

7. A conductor unit for a wiring system, comprising a cap member having a top and side walls, a base arranged to be positioned within said cap member, said base having an end portion for projection beyond an end of said cap member when said cap member and base are in operative association, electricity conductor means insulatedly mounted within said base and extending longitudinally thereof, and means for establishing the relative position of said cap and base members to gage the extent of projection of said base from said cap member.

8. A conductor unit for an electric wiring system, comprising a cap member having an open side, a base member arranged to be removably secured to said cap member and serving to close the open side thereof, said base member having an end projecting beyond an end of said cap member when in operative position with respect to said cap member, a plurality of electricity conductor means arranged within said unit and extending longitudinally thereof in mutually insulated status, and means for gaging the relative position of said cap and base member to establish the extent of projection of said base member beyond said cap member.

9. A conductor unit for a wiring system, comprising a cap member having a top and side walls depending therefrom, a base member arranged to be removably secured within said cap member, said base member having walls in engagement with the side walls of said cap member and in slidably tongue and groove relationship therewith, said base member having an end portion projecting beyond an end of said cap member when in operative association therewith, electricity conductor means arranged within said

unit in mutually insulated spaced relationship and extending longitudinally of said unit, and an abutment on one of said members for engagement by the other of said members to establish the relative position of said cap and base members and the extent of projection of said base member from said cap member.

10. A conductor unit for a wiring system, comprising a cap member having a top and side walls depending therefrom, a base member arranged to be removably secured within said cap member, said base member having walls in engagement with the side walls of said cap member and in slidably keyed relationship therewith, said base member having an end portion projecting beyond an end of said cap member when in operative association therewith, electricity conductor means arranged within said unit in mutually insulated spaced relationship and extending longitudinally of said unit, and an abutment on one of said members for engagement by the other of said members to establish the relative position of said cap and base members and the extent of projection of said base member from said cap member.

11. A conductor unit for a wiring system, comprising a cap member having a top and side walls depending therefrom, a base member arranged to be removably secured to said cap member, said base member having walls in engagement with the side walls of said cap member and said side walls of said cap and base members being in tongue and groove association one with the other, said base member having an end portion projecting beyond an end of said cap, and electricity conductor means arranged within said unit in mutually insulated spaced relationship and extending longitudinally of said unit, such tongue and groove relationship terminating at a predetermined position with respect to said base member to afford means for limiting the extent of projection of said base member from said cap member.

12. A conductor unit for a wiring system, comprising a cap member having a top and side walls depending therefrom, a base member arranged to be removably secured within said cap member, the side walls of said cap member having a re-entrant formation for engagement with the side walls of said base member to secure said base member to said cap member in a manner permitting only longitudinal displacement of said base member relative to said cap member, said base member having an end portion projecting beyond an end of said cap, electricity conductor means arranged within said unit in mutually insulated spaced relationship and extending longitudinally of said unit, and means for gaging the relative position of said cap and base members to fix the extent of projection of said base member from said cap member.

13. A conductor unit for a wiring system of seriatim interconnected units, comprising a cap member and a base member removably associated with said cap member, said cap member having means defining a socket portion at one end, said base member projecting from said cap member at the end opposite said socket portion, the projecting portion of said base member being arranged for insertion into the socket portion of a contiguous, similar unit, electricity conductors arranged within said unit and having terminal portions exposed at the ends thereof for interconnection with the conductors of contiguous, similar units, and means on one of said members

to establish the operative position of the other member relative thereto, whereby uniformity of the extent of projection of said base member may be obtained.

14. A conductor unit for a wiring system of seriatim interconnected units, comprising a cap member and a base member removably secured thereto, said cap and base members cooperating when in assembled status, to provide a socket at one end of the unit and a male projecting portion at the opposite end, electricity conductors arranged within said unit and having terminals at the ends thereof for interconnection with conductors of contiguous, similar units, the points of such connection being wholly within said units and shielded from external contact by the walls thereof, and abutment means on one of said unit members to establish the position of the other member relative thereto and the extent of projection of the male portion thereof.

15. The method of shortening an electrical

conductor unit having a body portion and a cap therefor, comprising the steps of removing said body portion from said cap portion, reversing the normal directional relationship of one of said portions with respect to the other, aligning ends of said base and cap portions respectively, cutting through said cap and base portions to sever the unwanted surplus therefrom, and re-assembling said cap portion and said base portion in proper operative relationship.

16. The method of shortening an electrical conductor unit having a composite structure embodying separable elements, comprising the steps of separating said elements, reversing the normal position of one of said elements with respect to the other, severing the unwanted surplus from said elements by a cutting operation, and re-assembling said elements to restore the same to proper operative relationship.

20

JOSEPH F. O'BRIEN.
